ELECTRIC DOOR LOCK

Maurice J. Tassin, New Orleans, La.

Application December 31, 1948, Serial No. 68,710

2 Claims. (Cl. 175—320)

1

This invention relates generally to door locks or keepers and more particularly to an electric door lock which may be operated to open the door from the outside of the building, when predetermined ones of a plurality of numbered push buttons corresponding to the combination of the keeper are momentarily depressed in predetermined sequential order.

The present invention contemplates a combination type door lock of the aforescribed character which is convenient and simple to operate when the correct combination is applied and which is as effective to maintain the door in a locked condition as the conventional key type lock while eliminating the need for a key or keys and thereby obviating the inherent difficulties in the use thereof due to the human element or factor involved in the usual handling, hiding, losing or distribution of individual keys among members of a family.

According to the arrangement of the present invention, an electric door opener is operated under control of a plurality of relays individual to numbered buttons, the electrical connections between the relays and buttons being such as to render each successive relay effective to be operated as the button individual thereto is depressed in the proper sequential order according to the combination of the keeper. When the last relay is operated by the button corresponding to the last number in the combination, the electric door lock is operated under control thereof, thereby to allow the door to be opened.

As each of the relays is operated, a lock-in circuit therefor is established thereby, and this circuit, in addition, applies potential to the next succeeding button to be depressed according to the combination. Other ones of the aforementioned plurality of numbered buttons which do not form a part of the combination are so constructed as to be normally closed and are arranged in the aforesaid lock-in circuits of the relays whereby the relays are de-energized when any one of the normally closed buttons are opened as the buttons are depressed. In such case, depressing of the proper buttons must be begun again and continued in the combination sequence to allow the opening of the door.

The buttons and relays respectively are arranged in boxes therefor located in any convenient manner on the exterior and interior of the building wall respectively, these boxes preferably being arranged in each case as inserts within the wall with cover plates therefor, all in a manner to be more fully described as the specification proceeds.

2

An object of the present invention is to provide an electric door lock having all the advantages of a key type lock while obviating the disadvantages thereof which flow from the need for use of a key.

Another object is to provide an electric door lock which may be operated to allow the opening of a door from the outside of a building by pressing a series of numbered buttons in predetermined sequential order according to the combination of the keeper.

A further object is to provide an electric door lock of this character wherein provision is made for restoring the same to an initial unoperated condition when a numbered button not forming a part of the combination is depressed.

An additional object of the invention is to provide a door lock of the aforescribed character which may be set or arranged to operate on any one of a plurality of different combinations and which readily may be adapted and applied to all types of doors regardless of the shape or construction thereof or that of the building structurally associated therewith.

Still other features, advantages and objects of the present invention not expressly set forth hereinbefore are those inherent in or implied from the novel combination and arrangement of parts as will become more clearly apparent from the following description of the preferred embodiment of the invention disclosed in the accompanying drawings wherein:

Figure 1 is a view in elevation illustrating a fragmentary portion of a building having the button and relay boxes of the present invention mounted thereon;

Figure 2 is a sectional view taken along the line 2—2 of Figure 1;

Figure 3 is a front elevational view of the button box with the cover plate removed and with the depressor buttons shown in section, substantially as seen along the line 3—3 of Figure 4;

Figure 4 is a sectional view of the button box as seen along the line 4—4 of Figure 3, the cover plate also being shown;

Figure 5 is a fragmentary sectional view of the box as seen along the line 5—5 of Figure 4;

Figure 6 is a sectional view of the relay box substantially as seen along the line 6—6 of Figure 1, and

Figure 7 is a diagrammatic view of the complete electrical system of the present invention according to the preferred embodiment thereof.

Referring now to the drawings, for a more complete understanding of the invention and

more particularly to Figure 1 thereof, there is shown thereon a fragmentary portion of a building 10 upon whose exterior surface there is mounted as by screws 11, or the like, a cover plate 12, which may be made of brass or other weather resisting material suitable for the purpose.

Plate 12 covers an opening in the building wall within which is inserted a metal box 13 whose open end is also closed by the cover plate. Box 13 preferably is provided with an apertured flange 14 at the open end thereof whereby the box may be secured to the wall as by the countersunk head screws 15, or the like.

Within box 13 and maintained in fixed spaced relation with respect to the bottom thereof as by the side strips 16, there is mounted an insulating plate 17 composed of a suitable insulating material such, for example, as Bakelite or fibre board. Upon plate 17, on the inner side thereof, and in any conventional manner, there are mounted two horizontally disposed rows of button switches having five switches to the row. These switches are identified by the legends PB1 through PB0 and may be of identical construction except for the initially open or closed condition of their single pole, single throw switch contacts. Each switch has a depressible button 18, which upon being depressed, opens or closes its associated switch contacts, as the case may be.

The actuating buttons 18 pass through suitable openings therefor in cover plate 12 which has engraved or otherwise formed therein the numerals associated with switches PB1 to PB0 inclusive, and respectively numbered one to ten, i. e., 1 to 0, inclusive.

The leads or conductors 19 from the button switches pass out of switch box 13 as at 20 and 21 to form a supply cable 22 and an intermediate cable 23 which passes within wall 10 and into the metal relay box 24 through opening 25 thereinto to connect with relays mounted within the box. Box 24 preferably is mounted within an opening formed on the interior surface of the wall and secured thereto by countersunk head screws 26, box 24 also preferably having an apertured mounting flange or lip 27 for receiving screws 26. The open end of box 24 is closed by a suitable cover plate 28 secured to wall 10 as by screws 29, or the like.

Leads or conductors 30 from cable 23 pass within relay box 24 to a plurality of relays designated relay 1, relay 2, relay 3 and relay 4, these relays being of a conventional type and mounted in any conventional manner on an insulation plate 31, which may be formed of any insulation material suitable for the purpose such, for example, as Bakelite or fibre board.

Plate 31 is maintained in fixed spaced relation with respect to the bottom of box 24 by means of the metallic strips 32 to which it is secured by rivets or the like as at 33.

The relays are identical except that in the case of relay 4, two sets of normally open contacts are employed, the other relays having one set of contacts. The second set of contacts of relay 4, are connected by a cable 34 which passes out of box 24 as at 35 to make connection with the secondary winding 35 to Figure 7, of transformer 36 and the actuating winding 37 of the electric door lock generally designated 38.

Referring now to Figure 7 for a more complete understanding of the manner of operation of the electric combination doorkeeper of the present invention, let it be assumed that the door

39 is locked, as illustrated, the bolt 40 being urged into a keeper 41 in the door as by the spring 42.

For the purposes of illustration, the button switches and relays have been wired to open the electric door lock 38 on the combination 90—6—3—2. It will be understood, however, that the wiring may be arranged to provide numerous other different combinations. Moreover, to provide the combination 90, push button switches 9 and 0 are connected in series, thereby requiring only four relays. When five single numbers are employed, i. e., in a combination 9—0—6—3—2, five relays are required. The operating principle in either case is the same, however.

To set up the aforesaid combination of 90—6—3—2, the switch contacts of button switches PB2, 3, 6, 9 and 0 are normally open and are connected in series with line 1, whereas the contacts of switches PB1, 4, 5, 7 and 8 are normally closed and are connected in series with line 2, lines 1 and 2, being supplied, for example, from secondary winding 43 of transformer 36, whose primary winding 44 may be supplied from a conventional 110 v., A. C. source. It will be understood that D. C. voltages may be employed when desired and any suitable magnitudes of either D. C. or A. C. voltages may be employed, commensurate with the operating voltages of the relays.

Now to operate the door lock, buttons 9 and 0, are first momentarily depressed concurrently, thereby to complete a circuit to relay 1, from line 1, by way of switch contacts PB9 and PB0, conductors 19A and 30A, to the operating coil of relay 1, conductor 30B, conductor 19B, and thence through switch contacts PB8, PB7, PB5, PB4 and PB1 to line 2. As relay 1 operates, its normally open contacts 45 close to connect conductor 19A to conductor 19C which is an extension of line 1, thereby to establish a lock-in circuit for maintaining operation of relay 1 from lines 1 and 2, after switches PB9 and PB0 open upon release of actuating buttons 9 and 0 and to apply potential at line 1 to switch PB6.

Thus, when button 6 is depressed to close switch PB6, line 1 potential is applied by way of conductors 19D and 30C to relay 2. Since the other side of relay 2 is connected by way of conductors 30D and 19B to line 2, through normally closed switches PB8, 7, 5, 4, and 1, relay 2 operates to close its normally open contacts 46.

As contacts 46 close, conductor 19D is connected to conductor 19C and line 1 thereby to establish a lock-in circuit for maintaining the energization of relay 2, after switch PB6 is opened upon release of button 6 and to apply potential at line 1 to switch PB3. Thus, when button 3 is depressed to close switch PB3, line 1 potential is applied by way of conductors 19E and 30E to relay 3. Since the other side of relay 3 is connected by way of conductor 30F and 19B to line 2, through normally closed switches PB8, 7, 5, 4 and 1, relay 3 operates to close its normally open contacts 47.

As contacts 47 close, conductor 19E is connected to conductor 19C and hence to line 1, whereby a lock-in circuit is established to maintain the energization of relay 3, after switch PB3 is opened upon release of button 3. Contacts 41 also apply line 1 potential to switch PB2 by way of conductor 19E whereby, when button 2 is depressed to close switch PB2, line 1 potential is applied by way of conductors 19F and 30G to relay 4. Since the other side of relay 4 is con-

nected by way of conductors 30H and 19B to line 2 through normally closed switches PB8, 7, 5, 4 and 1, relay 4 operates to close its two pairs of normally open contacts 48 and 49.

As contacts 48 close, conductor 19F is connected to conductor 19C and hence to line 1, whereby a lock-in circuit is established to maintain the energization of relay 4, after switch PB2 is opened upon release of button 2. As contacts 49 close, an obvious circuit is completed from transformer secondary to the actuating coil 37 of electric mortise 38 whereby bolt 40 is withdrawn from mortise 41 and the door is opened.

It will be noted from the foregoing that the lock-in circuits for the relays in each case are completed through the normally closed switches PB8, 7, 5, 4 and 1. Thus, upon depressing any one of the buttons corresponding to these switches, after the combination has been started or completed the relays which have been operated are released and the keeper is restored to its initial unoperated condition, and the combination must be started again if the door is to be unlocked.

It should be noted further that a simultaneous closing of switches PB2, 3, 6, 9 and 0, will also allow opening of the door. However, such operation is inconvenient and cannot readily be accomplished without also actuating one of the normally closed switches, the actuation of any of which latter switches would prevent operation of the relays through their initiating or starting as well as through their lock-in circuits.

From the foregoing it should now be apparent that I have provided an electric combination doorkeeper, which is well adapted to fulfill the aforesigned objects of the invention. Moreover, whereas the invention has been disclosed in particularity with reference to a preferred embodiment which gives satisfactory results, it will be understood by those skilled in the art to which the invention most nearly appertains, that additional embodiments and modifications thereof may be provided without departing from the spirit and scope of the invention as defined by the appended claims.

Having described the invention, what is claimed as new is:

1. An electric door lock of the character disclosed comprising an end circuit, a plurality of 59 relays, circuit means including a plurality of normally open push button switches numbered in accordance with the numbers of a preselected combination and arranged to operate said relays in predetermined sequential order as said switches are closed in sequence according to the number sequence of the combination, circuit means controlled by the last of said relays to be operated for closing said end circuit as said last of the relays operates, a plurality of lock-in circuits individual to said relays and adapted to be rendered effective as the relays operate to maintain the energization of the relays after the switches individual thereto have been opened, said lock-in circuits individual to all but said last of the relays being effective to render the next succeeding switch in the combination effective to operate the relay individual thereto as the switch is closed, and a plurality of normally closed and numbered

push button switches included in series circuit in said lock-in circuits whereby the lock-in circuits are interrupted thereby to restore the keeper to an initial unoperated condition when any one of 5 said normally closed switches is opened after the combination is applied to the keeper.

2. An electric door lock including an end circuit, a plurality of normally open push button switches numbered in accordance with the numbers of a preselected combination and connected in series in the order corresponding to the number sequence of the combination, a plurality of normally closed and numbered push-button switches arranged in series connection with respect to each other, first, second, and third relays each having a pair of normally open contacts adapted to be closed as the relay operates, a fourth relay having two pairs of normally open contacts adapted to be closed as the relay operates, a first circuit including said first relay, said series connected normally closed switches, and the series connected switches corresponding to the first and second numbers of the combination for energizing the first relay as the last named switches are closed concurrently, a second circuit including second relay, the contacts of the first relay, said series connected normally closed switches, and the switch corresponding to the third number of the combination for maintaining the energization of the first relay upon closing of the contacts thereof as the first relay operates and for energizing the second relay when said last named switch is closed, a third circuit including said third circuit including said third relay, the contacts of the second relay, said series connected normally closed switches, and the switch corresponding to the fourth number of the combination for maintaining the energization of the second relay upon closing of the contacts thereof as the second relay operates and for energizing the third relay when said last named switch is closed, a fourth circuit including said fourth relay, the contacts of the third relay, said series connected normally closed switches, and the switch corresponding to the fifth number of the combination for maintaining the energization of the third relay upon closing of the contacts thereof as the third relay operates and for energizing said fourth relay as said last named switch is closed, a fifth circuit including one pair of the contacts of the fourth relay and said series connected normally closed switches for maintaining the energization of the fourth relay upon closing of the contacts thereof as the fourth relay operates, and a sixth circuit including the other pair of contacts of the fourth relay and said end circuit as the fourth relay operates.

MAURICE J. TASSIN.
